UNITED STATES PATENT OFFICE.

SIGVERT SEVERY DAHL, OF VIRGINIA, MINNESOTA.

METAL TELEPHONE-DIRECTORY HANGER.

1,405,298.

Specification of Letters Patent.

Patented Jan. 31, 1922.

Application filed May 10, 1920. Serial No. 380,272.

To all whom it may concern:

Be it known that I, SIGVERT SEVERY DAHL, a citizen of the United States, residing at Virginia, in the county of St. Louis 5 and State of Minnesota, have invented a new and useful Metal Telephone-Directory Hanger, of which the following is a specification.

My invention relates to a device by which 10 a metal arm is attached to a desk or wall telephone, a wall, desk, or any other place where it is convenient to have or keep a telephone directory.

The object of my invention is to provide 15 a hanger for a telephone directory; said hanger to be hung in a convenient manner and place with the said directory attached to said hanger, with the result, that said directory can always be found and will always 20 be properly cared for, thereby saving time and eliminating annoyance to the persons using the telephone and directory.

I attain this object by the device illustrated in the accompanying drawing, in 25 which I show the said hanger attached to any ordinary desk telephone.

Figure 1 is the top view of the metal arm of said hanger, which attaches to a telephone, wall, desk or other convenient place; 30 Figure 2 is an end view of same; Figure 3 is a side view of same; Figure 4 is a side view of the metal hanger which attaches to a telephone directory and is suspended from the said arm; Figure 5 is a top view of 35 same; Figure 6 is a front view of same; Figure 7 shows the front view of the arm attached to a desk telephone with a telephone directory attached to said metal hanger, which hanger is shown suspended 40 from said arm; Figure 8 shows the side view of same.

Similar numerals refer to similar parts throughout the several views.

In Figure 1, arm 1 has a hook 2 on the 45 end with a slot 3 in it and a slight enlargement 4 of the end of said slot serves to give more freedom of action when the said directory is in use while the hanger is attached to the said arm. A short piece 5, of the 50 other end of the arm is bent at right angles to the said hook and contains a hole 6, through which passes the screw bolt 7, by which the said arm is attached to the telephone, wall, desk or any other convenient 55 object or place as desired. Arm 1 and piece 5, or either of them, may be bent at any

angle or in any direction, when same is manufactured, to satisfy the user and to further the convenient attaching of the said arm to different objects in different arrangements.

In Figure 4, part 8 fastens to the said directory by a screw bolt passed through said directory and holes 9 in said part 8. The round T shaped bar 11 passes through the 60 slot 3 and hangs on hook 2 when the said directory is not in use. When using the said directory the said T bar is raised up into the circular enlargement 4, of the said slot, allowing freedom of action in opening 65 and using said directory in a convenient position to the user thereof.

If the user wishes to take the directory off the hook, this may be done by turning the T bar around so that it can be pulled 70 out through the slot and the T bar being fastened at the middle of the bound edge of the said directory will thus form a convenient handle.

In Figures 7, and 8, part 12 represents 75 the mouth piece and part 13 a portion of the stand of a desk telephone while 14 represents a telephone directory.

I do not claim any improvement on the telephone itself.

All of the said parts of said device may 80 be made of any metals desired and in any sizes. The metal may be treated in any manner, as to appearance, to suit the individual taste of the user.

What I claim as new is:

1. A telephone hanger in the form of a horizontally disposed hook which has a slot in the hook which extends throughout the entire length of the bend of the hook, in 95 combination with a T-bar hanger removably held in the slot and capable of being slid from one end to the other of the slot and when so moved having its position entirely reversed or inverted.

2. The combination with a support having a horizontally disposed hook at its free end which is slotted throughout the bend of the hook, of a T-bar hanger inserted in the slot and capable of being turned therein 105 from a depending or hanging position, to the reverse or an upstanding position, the upper end of the slot terminating in a circular enlargement which allows freedom of action in opening and using the article held 110 by the hanger.

SIGVERT SEVERY DAHL.
